UNITED STATES PATENT OFFICE.

GEORG KIRKEGAARD, OF NEW YORK, N. Y.

BOTTLE-STOPPER.

No. 873,867.

Specification of Letters Patent.

Patented Dec. 17, 1907.

Application filed October 11, 1906. Serial No. 332,358.

To all whom it may concern:

Be it known that I, GEORG KIRKEGAARD, a citizen of the United States, and a resident of the city of New York, in the county of New York and State of New York, United States of America, have invented certain new and useful Improvements in Bottle-Stoppers, of which the following is a specification.

10 My invention relates to an improvement on a bottle stopper which I have invented and for which Letters Patent of the United States No. 829,341 were issued to me on the 21st day of August, 1906.

15 The present invention relates to an improvement which I have made in connection with this stopper for the purpose of indicating if the stopper has been used.

I will describe my invention in the following specification and point out the novel features thereof in claims.

Referring to the drawings, Figure 1 is a perspective view of my improved bottle stopper; Fig. 2 is a side elevation of the 25 same, and Fig. 3 is a side elevation, partly in section, of the upper portion of a bottle with one of my stoppers applied thereto. Fig. 4 is a sectional view of a bottle stopper cap, the section being taken through the line 30 X—X of Fig. 2 and the view being taken in the direction of the arrows. Fig. 5 is an enlarged sectional view of a portion of a specially constructed handle or tail-piece which I use in carrying out my invention. Fig. 6 is 35 a sectional view of the same part showing it in a different position. Fig. 7 is a side elevation of the part shown in Fig. 5, the view being taken at right-angles to that shown in Fig. 5.

40 Like characters of reference designate corresponding parts in all of the figures.

10 designates a cap which is constructed of sheet metal such, for example, as tin. This cap or stopper comprises a disk portion 45 11 which has an annular depending flange 12. These together form an inverted cup within which is placed a packing disk 13 of cork for other suitable material. At three points around the periphery of the disk and 50 at substantially equal distances apart are formed fingers 20, one of these being extended as shown at 21, 21 to form a handle or tail-piece.

The fingers are embossed or pressed in a 55 manner or for the purpose fully set forth in an aforesaid Letters Patent No. 829,341, so

that each of them has a hollow lug 22 which is arranged to engage with the inclined shoulder 31 of the bottle 30 to which the stopper is to be applied, and stiffening ribs 60 23 which extend from points over the edge of the disk 11 downward and below the holding lugs 22. Between the ribs the metal of the flange 12 is bulged outward above the projecting lug 22 as indicated at 24, so that the 65 whole structure of the finger is far more rigid and strong than the remaining portions of the flange and disk. The flat portion designated by 25 is provided for the purpose of accomplishing the operation of applying the 70 cap to a bottle by means of a die or other tool which may be arranged with cam-surfaces which come in contact with these surfaces for this purpose and thus the flattening out and destroying the function of the stiffening 75 ribs 23 by this operation is avoided.

In applying this stopper to a bottle or jar a die or other tool is used for pressing the disk down upon the mouth of a bottle so as to compress the packing material 13 and then 80 pressing the lower portion of the fingers 20 into engagement with the annular shoulder 31 of the bottle. The cap thus secured to the bottle is held firmly in place by the strength of the fingers, and it is capable of 85 withstanding considerable pressure from the inside of the bottle. When it is desired to remove this cap from a bottle this may be readily done by grasping the lower end of the tail-piece or handle 21 and forcing the 90 cap upward thereby. This operation does not materially change the cap and its fingers as when it is thus sprung off from the bottle the stiffness of the structure will cause it to immediately regain its original shape. If it 95 is desired to reseal the bottle after this operation this may be readily done by simply placing the cap over the mouth of the bottle and pressing downward upon the disk 11 until the fingers 20 snap under the shoulder 31. The 100 pressure of the lugs 22 upon the inclined shoulder will hold the cap upon the bottle with sufficient strength to effectually seal the bottle.

The structure thus far described and the 105 operation of this device is more fully disclosed in the aforesaid Letters Patent. In some cases it is desirable to provide means for showing if this cap has been used. For this purpose I provide in the handle or tail-piece 21 grooves or indentations 21^a in both sides of the tail-piece near its lower extrem-

ity. These are clearly shown in Figs. 5, 6 and 7. These grooves divide the lower end 21^b of the handle or tail-piece from the rest of the structure. It may be seen that the 5 groove in the tail-piece proper 21 is made on the inner surface of the metal while the groove which passes through the stiffening rib 23 is on the outer surface of the metal. When a cap provided with these grooves is 10 first applied to a bottle in the usual manner these grooves perform no function whatever, but when the cap is removed in the manner already described, the first pressure applied to the lower end of the handle or tail-piece 15 for the purpose of removing the cap will cause the lower end 21^b to bend outward as shown in Fig. 6 and also in dotted lines in Fig. 3. This lower portion will facilitate the operation of removing the cap as it provides 20 a better finger hold and therefore may be more readily manipulated. After a cap has thus been removed the lower end 21^b of the tail-piece 21 will remain bent outward so that it will show that the cap has been used. 25 If an attempt is made to bend this portion 21^b down again into its original position it will break off at the grooves 21^a, 21^a, as the bending of the metal at this point will so strain or fracture the fibers of the metal that 30 it will break through if it is bent back again.

The cap or stopper which I have herein described possesses all of the advantages disclosed in the former Letters Patent and it has the additional feature of indicating whenever it has been removed after it is first applied to a bottle.

What I claim is.—

1. A bottle stopper comprising a disk having an annular depending flange, fingers extending downward beyond the flange, said 40 fingers being provided with holding portions adapted to engage with the neck of a bottle,

and a handle or tail-piece extending from one of the fingers; said tail-piece being provided with a fracture groove below the holding portion of the finger from which it extends so that the lower portion of the tail-piece constitutes an indicating device. 45

2. A bottle stopper comprising a metallic cap containing a packing material and having a number of depending fingers around its periphery, each finger having an inwardly projecting lug for engaging the neck of a bottle, stiffening ribs surrounding said lugs and extending upward to the cap, and a handle 50 or tail-piece extending from one of the fingers; said tail-piece being provided with a fracture groove below the inwardly projecting lug of the finger from which it extends so that the lower portion of the tail-piece constitutes an indicating device. 55

3. A bottle stopper comprising a sheet metal cap containing a packing material, said cap having a disk, a depending annular flange and fingers extending from the lower 60 edge of said flange around its periphery, each of said fingers being provided with a reinforcement extending from its lower end upward through the width or depth of the flange and an inwardly projecting lug for 65 engaging the neck of a bottle, and a handle or tail-piece extending from one of the fingers; said tail-piece being provided with a fracture groove below the inwardly projecting lug of the finger from which it extends so 70 that the lower portion of the tail-piece constitutes an indicating device. 75

In testimony whereof I have signed my name to this specification in the presence of two subscribing witnesses.

GEORG KIRKEGAARD.
